UNITED STATES PATENT OFFICE.

HARMER DENNEY, OF BROOKLYN, NEW YORK.

CLUTCH.

SPECIFICATION forming part of Letters Patent No. 446,664, dated February 17, 1891.

Application filed May 28, 1890. Serial No. 353,420. (No model.)

To all whom it may concern:

Be it known that I, HARMER DENNEY, of Brooklyn, in the county of Kings and State of New York, a citizen of the United States, 5 have invented certain new and useful Improvements in Clutches, of which the following is a specification.

This invention relates to improvements in clutches such as are used for driving one 10 piece of machinery from another, and especially where the direction of rotation of certain parts of the machinery is to be reversed rapidly and without lost motion.

The invention consists in the construction 15 and combination of parts and details, as will be fully described hereinafter, and finally pointed out in the claims.

In the accompanying drawings, Figure 1 is a plan view of my improved clutch. Fig. 2 20 is a vertical longitudinal sectional view of the same. Fig. 3 is a vertical transverse sectional view of the same on the line 3 3, Fig. 1; and Fig. 4 is a similar view on the line 4 4 of Fig. 1.

25 Similar letters of reference indicate corresponding parts.

The spindle or shaft H is provided with two collars N and O, which are fixed thereon, and between the same an eccentric P is fastened on said spindle, and said eccentric P is 30 surrounded by another eccentric Q, which is loose thereon. The two eccentrics are so arranged that the thicker part of one eccentric is adjacent to the thinner part of the other, 35 as shown in Fig. 4, and the circumference of the outer eccentric Q is concentric with the spindle or shaft H. The outer eccentric Q is provided with an outwardly-projecting lug Q', which is arranged between the adjacent 40 ends of two collars S, mounted to turn with and to slide lengthwise on two sleeves R, mounted loosely on the shaft or spindle H, and which sleeves are each provided with a cog-wheel R', engaged with gearing for rotating them in opposite directions. Each collar S has a circumferential groove, into each 45 of which the prongs of a fork S' pass, said forks being secured on a longitudinally-sliding rod S².

50 As shown in Fig. 2, the spindle or shaft H

is engaged with the right-hand sleeve R and is rotated with the same, the left-hand sleeve R being disengaged from the shaft or spindle. If now the rod S² is moved in the direction toward the right, both the collars S 55 are moved toward the right, and the pin S⁵ on the right-hand collar S is moved out of the path of the lug Q' on the eccentric Q, and the pin S⁵ on the left-hand collar S is moved into the path of the lug Q' and will eventually 60 strike that lug, thereby turning the outer eccentric Q slightly on the inner eccentric P, thereby causing said eccentric Q to bind on the left-hand sleeve R, at the same time disengaging the eccentric Q from the right-hand 65 sleeve R, so that thereby the motion of the spindle or shaft H is reversed. If the rod S² is moved in the direction toward the left, the pin S⁵ on the left-hand collar S is moved out of the way of the lug Q', and the pin S⁵ 70 on the right-hand collar S is moved in the path of the lug Q', which it strikes, thereby turning the eccentric Q so that it binds on the right-hand sleeve R and is disengaged from the left-hand sleeve R, whereby the direction of rotation of the shaft or spindle H is again reversed.

75 The above-described reversing-clutch has also been shown and described in my application, Serial No. 341,934, filed December 27, 1889, for a machine for making tubing; but I do not claim the herein-described invention in the said application No. 341,934.

Having thus described my invention, I claim as new and desire to secure by Letters 85 Patent—

1. The combination, with a shaft or spindle, of an eccentric fixed on the same, a reversed eccentric mounted loosely on the eccentric fixed on the shaft and having a projection, two sleeves mounted loosely on the shaft or spindle, means for rotating the sleeves in opposite directions, and sliding collars keyed on said sleeves and having pins projecting toward each other, the projection on the loose 90 eccentric being between said sliding collars, substantially as set forth.

2. The combination, with a spindle, of a fixed eccentric on the same, a reversed eccentric mounted loosely on the eccentric fixed 95

on the spindle and having a projection, two sleeves on the spindle at opposite sides of the eccentrics, means for turning the outer eccentric to bind on either one of said sleeves, and 5 means for rotating said sleeves in opposite directions, substantially as set forth.

In testimony that I claim the foregoing as

my invention I have signed my name in presence of two subscribing witnesses.

HARMER DENNEY.
